UNITED STATES PATENT OFFICE.

WILLIAM BAYLEY, OF SPRINGFIELD, OHIO.

LANTERN-WINDOWS AND THEIR OPERATING MECHANISM.

1,025,957.

Specification of Letters Patent.

Patented May 14, 1912.

Application filed April 18, 1911. Serial No. 621,941.

To all whom it may concern:

Be it known that I, WILLIAM BAYLEY, citizen of the United States, residing at Springfield, in the county of Clark, State 5 of Ohio, have invented certain new and useful Improvements in Lantern-Windows and Their Operating Mechanism, of which the following is a specification, reference being had therein to the accompanying drawings.

10 This invention relates to the construction of ventilators for building roofs, usually termed monitors or lanterns, to the manner of assembling the truss members, to the manner of applying windows to the sides, 15 to the hinging of the windows, to the manner and direction of opening the windows, to the manner of operating a long line of such windows.

Heretofore, the framing of the truss members of a lantern has always contemplated a post on the outside on each side, against the outside of which, (and extending from under the eave of the lantern roof down to the main roof), window frames have been 20 secured. These frames, have been constructed with the window sills raised about one foot above the main roof, this one foot raise being necessary on account of keeping snow from banking up, or rain from splashing up and 25 over the sill. Sometimes these window frames have been divided up into short spaces between the trusses and narrow window sashes pivoted on the vertical center of each. These sashes have either been operated 30 independently, or have been connected together and operated by one mechanism from one point. Each side of the lantern being operated independently, or a continuous window sash has been installed and hinged to 35 the top of the lantern side, just under the eave of its roof and arranged to open outward at its lower edge. Neither of the above 40 plans can get rid of this one foot height from the main roof to the window sill and therefore 45 cannot take advantage of the whole height of the lantern side for ventilation or the admittance of light. And both of the plans mentioned above have the objection of opening out beyond the projection of the 50 eaves of the roof, and are liable to exposure to hail and other outside agencies, both in the nature of tending to break the glass and to deposit on it soot and dirt washed from off the lantern roof. This invention 55 contemplates the construction of the truss members of a lantern so that there is no post on

the outside. The weight of the eave of the lantern roof being taken by an inclined post that carries the weight to a point higher up on the main truss. The lantern window 60 is made continuous and hinged at the bottom. The hinge is a knife edged hinge to all practical purposes. The bottom of the sash is V shaped and sets onto a stationary hinge edge. The edge of the window hangs 65 down on the outside of the hinge edge. This construction seals the hinge point against snow or rain and makes practical the dropping of the hinge point down close to a main roof, and in this way gaining a foot in 70 height. This gain of a foot can be made use of in two ways, to gain more ventilation to allow the making of the windows higher, or if the ventilation is considered sufficient, then the lantern can be lowered in height 75 and consequently lessened in cost. The V on the bottom of the window sash is made sufficiently angular to allow the sash to be opened inwardly at the top to the desired position. The inclined post that has been 80 mentioned is placed high enough to clear the top edge of the window sash as it opens inwardly on a radial line from the hinge center. And any braces in the structural part of the lantern truss are kept out of the way 85 of opening the window sash inwardly. Then the points gained over the old construction are more ventilation and light, or the same ventilation for less height. Complete protection from ordinary outside agencies of 90 breakage. Complete protection from dirt deposits and soot from off of the lantern roof, and more light with the same area of sash not only because of more cleanliness, but because it is practical to construct the 95 roof of the lantern with less overhanging eave, and in this way the light can pass more directly down through the opening.

In the framing of the window sash, a Z bar has been used at the bottom, it being the 100 best form to favor the supporting of the glass and the intermediate bars of the sash, it has fingers riveted to it to make the V hinge point. At the top of the sash a strong angle has been used, strong enough to resist 105 the bending strain from the wind pressure on the outside and between the lantern trusses. And under the eave of the lantern roof, a strong purlin is located, against which the top of the window sash closes. 110 There is no chance for the window to leak at this point. Located and pivoted on each

truss and connected at one leg to the window sash by a rod and joints, is a bell crank, the other leg of the crank, has pivoted into it, a clamp for a cable. The arrangement is such that the cable runs lengthwise through the lantern, and there is a strut running from truss to truss, adjacent to the bell crank centers to resist the pull of the operating cable.

10 In the drawings Figure 1 represents a view of the top of the main truss with lantern extension built on, it shows the roof between the trusses with its purlins in section, it shows the strut at the bell crank centers in section, and also the sash in section. Fig. 2 is an inside view of the window sash and a section of the truss on the line M M M M M M projected from Fig. 1. Fig. 3 is an enlarged section of the window sash with hinge and cap. Fig. 4 is a section across the entire lantern between the trusses on the line T T, Fig. 9, it shows the window sashes open and shows the ventilation currents. Fig. 5 shows a plan of the bell crank with its motion and its connection to the window sash and to the cable, it shows a section of the truss member on S S, and is projected from Fig. 1. Figs. 6, 7, 8, show plan, side, and end views respectively 30 of the cable clamp.

The numeral 1 represents the top chord of a main truss, 2 is the inclined post of the lantern truss, 3 is a brace in the lantern truss, 4 is a top chord of a lantern truss, 5 is a purlin of its main roof, to the side of which a strip 5' is secured and support the the sheathing 5''. On the top of purlin 5, flashing 6 is laid and clamped down by the hinge angle 7, which angle runs continuous 40 along the roof, 4' is the sheathing of the lantern roof, 4'' are the comb purlins of the lantern roof and 8 is an eave purlin of the lantern roof, the eave purlin 8 supports the roof, and also makes a strong cap for the 45 window top 9 to close against, at the bottom of the window sashes is a Z bar 10, this Z bar has fingers 10' riveted to it. The Z bar 10 and its finger 10' form a V that rests on the hinge angle 7. The Z bar 10 and the 50 top angle 9 are connected by vertical T window bars 11. The bottom end of the head of the T bar 11 is bent out into knee 11' and rivets on top of the Z bar. The top end of the T bar is also offset and rivets against the back of the angle 9. In this way the 55 under side of the head of the T is brought flush or in line with the side of the angle 9 and the Z 10, making a flat surface for the glass to lay against and be puttied in.

60 This invention does not comprehend any special way of securing the glass 12 into the sashes. When the window is shut as shown in Figs. 1, 2, 3, 9, 10, the center of gravity is outside of the hinge point 7', (see Fig. 3) 65 and the disposition is to remain closed un-

less wind should press against the sashes. And in order to hold the sashes shut and also to open them when necessary. At each truss along the building, bell cranks 13 are pivoted to the braces 3, and to angle struts 14, by knees 14', and a pin 15. The end U of the bell crank 13 is connected by two pins and a knuckle joint 16 to the rod 17. And the rod 17 is also connected by two pins and a knuckle joint 16 to knees 18, which are riveted to the top 9, of the window sashes. Thus the connection between the bell cranks to the window sashes is established, and if the bell cranks work in unison, then the sashes will be held close throughout their entire length and will be opened evenly. And to do this, at the end W of the bell crank 13, a clamp 19 is pivoted, clamp 19 consists of the back 19' which is pivoted into the bell crank permanently, and the cap 19'' which is bolted to the back 19' by the bolts 20. The cable 21 is stretched taut through the building from end to end, and through its connection with the bell cranks, operates the ventilator windows.

Having fully described this invention, what is claimed as new and desired to secure by Letters Patent, is:

1. A supported main roof provided with a lantern opening along it, a lantern construction involving posts and rafters upholding a lantern roof above the lantern opening, vertical spaces from the main roof at the edges of the lantern opening to the undersides of the lantern roof, window sashes adapted to fill said vertical spaces, and the side posts of the lantern construction set in from the edge of the lantern opening, to permit of window sashes being swung open inwardly into the space provided by setting the post in.

2. A main roof supported by trusses, with a lantern opening along it, within the opening a lantern construction involving posts, rafters and roof is supported by the trusses and held above the lantern opening, the outside posts of the lantern construction inclined inwardly from bottoms to tops, the lantern roof extending out beyond the edges of the lantern opening, vertical spaces from the main roof at the edges of the lantern opening to the undersides of the lantern roof in which to place window sashes, angles secured on top of the main roof at the edges of the lantern opening with one leg projecting upward, downward projecting shoulders under the edges of the lantern roof placed vertically above said angles, and a separate window sash with means to open it inwardly at the top closing each side of said lantern between said angles and said shoulders.

3. A supported main roof provided with a lantern opening along it, angles with one leg projecting upwardly, secured to the

main roof at the edges of the lantern opening, and within the opening a lantern construction, involving outside posts, rafters and roof, extending above said main roof,
5 the lantern roof extending out over the edges of the lantern opening, said lantern roof extensions having downwardly projecting shoulders under their outer edges and placed vertically above said angles on
10 the main roof, a separate long window sash closing each side of said lantern between said angles and said shoulders, and the outside posts of the lantern construction set far enough in from the vertical line of the
15 angles and shoulders to permit of long window sashes being swung open inwardly without interference from said posts.

4. A roof lantern construction involving in combination with roof rafters of lantern

truss bars supported at one end on said roof rafters at the edge of a lantern opening in the main roof and inclining upwardly and inwardly toward the roof of the lantern, transverse truss bars connected to the roof rafters crossing the first mentioned truss bars and lantern rafters connected at the ridge and eaves respectively, with the first and second mentioned truss bars, a longitudinal bar running from end to end of the lantern and connected to the truss bars at their points of intersection, side sashes for said lantern and operating means mounted at the intersections of the truss bars and the longitudinal bar.
